[57] CLAIM

The ornamental design for a decanter, substantially as shown and described.

DESCRIPTION

FIG. 1 is a right side perspective view of a decanter showing my new design;

FIG. 2 is a left side perspective view thereof;

FIG. 3 is a top plan view thereof;

FIG. 4 is a front elevational view thereof; and

FIG. 5 is a rear elevational view thereof;

The undisclosed bottom of the decanter is conventional in appearance.
